POSTING STAND

Samuel Segal, New York, N. Y., assignor to Wilson-Jones Company, Chicago, Ill., a corporation of Massachusetts

Application December 30, 1948, Serial No. 68,310

11 Claims. (Cl. 311—39)

1

This invention is a posting stand particularly although not necessarily adapted for use by bookkeepers, and one object has to do with conveniently controlled means for quickly setting the depressible platform thereof to selected and most suitable elevations. Another object resides in employing the platform in depressing the latter to actuate separable bars for collapsing toggle means pivotally relative to the base of the stand and against the resistance of adjustable spring means normally acting to maintain the toggle means extended. Another object is concerned with effectively operable accessible means for locking the separable bars against displacement relative to the platform to retain the latter at a selected elevation. Another specific object is realized in arranging the separable bars transversely of and within the platform to be guided by spaced rods sustained by and disposed longitudinally of the platform. A further object resides in utilizing abutment means cooperating with the slidably guided separable bars to compress the springs on downward displacement of the platform relative to the base. A further object resides in oppositely threading spaced portions of the guide rods to cooperate with similar threaded abutment means for shifting the latter towards or away from each other in the matter of adjusting the springs. Another important object is to provide spaced bearings sustained by the platform for rotatably guiding the spaced guide rods to displace threaded abutment means thereon in a direction towards or away from each other to compress or expand the adjustable springs. A still further object is concerned with an uninterrupted and partly threaded rotatable rod cooperating with partly threaded butterfly slots to detachably lock the slidably guided bars against displacement relative to the platform at selected elevations of the latter. A further object is to utilize the springs about the threaded guide rods to automatically shift the slidably guided bars towards each other upon unlocking of the interrupted rod from the walls of the partly threaded butterfly slots for automatically elevating the platform. Another object is to regulate the intensity of the springs to compensate for the type of load applied to the platform. Other important objects and advantages will be apparent from the following detailed specification considered with the teachings of the accompanying drawings wherein:

Fig. 1 is a perspective view of the posting stand according to my invention showing the slidably guided platform in its fully raised position.

2

Fig. 1A is a fragmentary perspective view of the control means for adjusting the tension of the load absorbing spring means.

Fig. 2 is a view similar to Fig. 1 but showing the platform fully depressed.

Fig. 3 is an underneath sectional view of the stand shown in Figs. 1 and 2 however taken on the line 3—3 of Fig. 4.

Fig. 4 is a vertical sectional and broken view on the line 4—4 of Fig. 3.

Fig. 5 is a transverse sectional view on the line 5—5 of Fig. 4.

Fig. 6 is an underneath sectional view on the line 6—6 of Fig. 2.

Fig. 7 is a sectional view on the line 7—7 of Fig. 6.

Fig. 8 is an enlarged transverse sectional view on the line 8—8 of Fig. 3.

Fig. 9 is a perspective view of the link carrying means and the associated locking means.

Fig. 10 is a sectional view on the line 10—10 of Fig. 9 illustrating the link carrying means unlocked.

Fig. 11 is a view similar to Fig. 10 showing the link carrying means locked.

Fig. 12 is a sectional view on the line 12—12 of Fig. 10.

Fig. 13 is a transverse view of one of the indicating blocks or spring abutments, and

Fig. 14 is a fragmentary view illustrating one of the abutment carrying rotatable rods mounted on a bushing sustained by the platform.

The posting stand generally denoted PS comprises channel shaped standards or posts 18 supported on the swiveled casters 11 and appropriately fixedly carrying the panel or base B having spaced depending flanges 12 straddling the lower portions of the transversely spaced expandible and contractible toggle systems each broadly denoted T. Each toggle system comprises pairs of lower links 13 having their upper ends pivotally connected to the lower ends of the intervening links or bars 14 in turn having their upper ends pivotally connected to the lower ends of the upper links 15 which have their intermediate portions carried and pivoted on fulcrum pin 16 while the intervening or intermediate links are suitably pivoted on the fulcrum pin 17.

Of importance to observe is that the upper ends of links 15 are each provided with an opening 18 (Fig. 8) pivotally surrounding studs 19 extending laterally of spaced bars or members 20. Axles or studs 19 carry rollers or wheels 21 adapted to roll against the inside surface 22 of the platform or table 23 provided with fixedly depending angle

shaped feet 24 slidably nested and retained by the corner columns or posts 10.

The depending front and rear flanges 26 of platform 23 closely straddle wheels 21 to preclude their accidental removal from their axles 19 which constitute fulcrum means for the upper links 15. The lower ends of links 13 of the toggle systems are pivotally sustained on the fulcrum rod 27 effectively carried by the spaced depending flanges 12 of the base B, there being spaced relief slots 28 provided in the base B to permit divergence of the lower links 13.

Extending longitudinally of and within platform 23 are the transversely spaced rods 30 which project through the unthreaded guide openings 31 in the spaced slidably guided bars or members 20. Each rod 30 is rotatably sustained in the bushings or bearings 32 each provided with a reduced portion 33 (Fig. 14) fitting into openings 34 in the flanges or spaced depending sides 35 of the platform.

Each rod 30 is provided with left and right threaded portions 36 and 37 respectively cooperating with corresponding internally threaded bores 40A in abutment blocks 38 and 39 each having a fixed indicating post 41 projecting into and displaceable relative to an associated slot 42 disposed near the indicia or graduation marks as 40, 70, 100 etc. on the top surface of platform 23.

In part surrounding spaced portions of the spaced rotatable rods 30 on which the transversely disposed slidably guided bars 20 are mounted, are the helicoidal springs 43 having ends abutting against blocks 38 or 39 and an adjacent slidably guided bar 20. The arrangement is such that when the platform 23 is depressed by the operator from its fully elevated position (Fig. 1) the slidably guided bars 20 separate further and act to compress springs 43 simultaneously against abutment blocks 38 and 39. Conversely when the force applied by the operator tending to depress the platform is removed, these springs automatically expand, hence urging slidably guided bars 20 towards each other, thereby actuating the upper ends of the upper links 15 towards each other whereby the toggles T expand, thus automatically raising platform 23.

For holding the platform in predetermined position of elevations in respect to base B, effective locking means is provided to prevent displacement of the parallel but slidably guided bars 20, such locking means taking the form of partly externally threaded or interrupted cylindrical rod 50 having the parallel flat faces 51 to define a reduced part 53. Attached fixedly to the enlarged portions 54 of rod 50 is the handle or crank 55 and rod 50 has a reduced terminal portion 44 rotatably guided in opening 45 in an associated flange 35 of the platform 23.

Where the spaced threaded portions 56 of the rods or shaft 50 are clear of internally threaded portions 57 (Fig. 11) of the "butterfly shaped" bores 58 in the spaced slidably guided driven bars 20, rod 50 is unlocked from both of the latter, thus permitting displacement of bars 20 towards or away from each other in case the platform is elevated or depressed respectively. Butterfly slots 59 also embody end portions 59 characterizing with the intermediate zone of the internally threaded portions 57 relatively elongating gaps appreciably wider than the diameter of the partly externally threaded reduced portions 53 of rod 50. If therefore handle 55 be operated to arrange shaft 50 to be clear and free of threaded portions 57 (Figs. 9 and 11) the bars 20 are thus

10

unlocked to permit their shifting relative to their spaced guide rods 30. This permits the platform to be adjusted to predetermined position of elevation, and such selected position is retained when the operating handle 55 is rotated about ninety degrees whereupon the spaced threaded parts 56 of shaft 50 interlock or engage with the spaced threaded portions 57 of the butterfly slots 58, thus retaining bars 20 in set positions, precluding displacement of the toggles T relative to the base.

According to the invention, the tension of springs 43 may be adjusted if desired. To this end each rod 30 is provided with a non-circular terminal 46 adapted to be actuated by a key K removably fitting into several of the end bushings 32 each carrying an adjustable threaded set screw 41. Consequently if the shafts 30 be rotated relative to respective bushings 32, abutment blocks 37 and 38 may be shifted towards or away from the spaced slidably guided bars 20 depending upon the extent of power desired in the springs 43 and such may be regulated by the aid of the graduation marks on the scales (Fig. 1) adjacent slots 42 in the platform.

Briefly recapitulating, the platform 23 of the posting stand is adapted to effectively support suitable books necessary for office operators who can quickly adjust the platform to a suitable elevation convenient for working. This is accomplished by first unlocking rod 50 and thereafter if the platform be at a high elevation it may be shifted to a more suited lower elevation by depressing the same. The platform is held in its selected position by turning rod 50 to lock the displaceable bars 20 against movement relative to the platform.

If the platform be in a lowered position the slidable bars 20 are unlocked from the locking rod 50 and the platform automatically elevated since the normal tendency of the helicoidal springs 43 is to urge the bars 20 towards each other thus extending the toggle systems.

Various changes may be made in details of construction and arrangement of parts without departing from the spirit of the invention or sacrificing any of the advantages thereof inherent therein.

I claim:

1. In a posting stand, a base, a platform, means carried by said base and platform for slidably guiding the latter towards or away from said base, apertured bars within said platform, roller means carried by said bars and riding against said platform, toggle means movably connected to said bars and base, rods carried by said platform, said rods projecting through the apertures in said bars and slidably guiding said bars lengthwise of said platform, abutment means on said rods, said abutment means being spaced from said bars longitudinally relative to said platform, and spring means interposed between said bars and abutment means to actuate said bars for extending said toggle means to elevate said platform.

2. In a posting stand, a base, a platform, means carried by said base and platform for slidably guiding the latter towards or away from said base, shiftable bars arranged transversely of said platform and having guide openings, roller means carried by said bars and riding against said platform, toggle means pivotally sustained on said base and having diverging portions movably connected to said bars, spaced rods carried by said platform and projecting through said openings for slidably guiding said bars lengthwise of said platform and each having oppositely threaded portions, spaced

abutment means, disengageable locking means to preclude displacement of said bars relative to said rods, and helicoidal spring means interposed between said abutment means and bars for actuating the latter to shift said diverging portions towards each other to extend said toggle means to automatically elevate said platform pursuant to unlocking of said locking means.

3. In a posting stand, a base, a platform, means carried by said base and platform for slidably guiding the latter towards or away from said base, shiftable bars arranged transversely of said platform and having guide openings, roller means carried by said bars and riding against said platform, toggle means movably interposed between said bars and base, spaced rods carried by said platform and projecting through said openings for slidably guiding said bars lengthwise of said platform and each having oppositely threaded portions, spaced abutment means on each of said rods and having cooperative threaded means engaging said oppositely threaded portions, disengageable locking means to preclude displacement of said bars relative to said rods, and helicoidal spring means interposed between said abutment means and bars for actuating the latter to extend said toggle means to automatically elevate said platform pursuant to unlocking of said locking means.

4. In a posting stand, a base, a platform, bearing means on said platform, means carried by said base and platform for slidably guiding the latter towards or away from said base, shiftable bars arranged transversely of said platform and having guide openings, roller means carried by said bars and riding against said platform, toggle means movably interposed between said bars and base, spaced rods rotatably carried by said bearing means and projecting through said openings for slidably guiding said bars lengthwise of said platform and each having oppositely threaded portions, spaced abutment means on each of said rods and having cooperative threaded means engaging said oppositely threaded portions, disengageable locking means to preclude displacement of said bars relative to said rods, and helicoidal spring means interposed between said abutment means and bars for actuating the latter to extend said toggle means to automatically elevate said platform pursuant to unlocking of said locking means.

5. In a posting stand, a base, a platform, bearing means on said platform, means carried by said base and platform for slidably guiding the latter towards or away from said base, shiftable bars arranged transversely of said platform and having guide openings, roller means carried by said bars and riding against said platform, toggle means movably interposed between said bars and base, spaced rods rotatably carried by said bearing means and projecting through said openings for slidably guiding said bars lengthwise of said platform and each having oppositely threaded portions, spaced abutment means on each of said rods and having cooperative threaded means engaging said oppositely threaded portions, disengageable locking means to preclude displacement of said bars relative to said rods, helicoidal spring means interposed between said abutment means and bars for actuating the latter to extend said toggle means to automatically elevate said platform pursuant to unlocking of said locking means, and key receiving means extending from said rods into said bearing means for rotating said rods for shifting said abutment

means towards or away from each other to vary the intensity of said springs.

6. In a posting stand, a base, a platform, bearing means on said platform, means carried by said base and platform for slidably guiding the latter towards or away from said base, shiftable bars arranged transversely of said platform and having guide openings, roller means carried by said bars and riding against said platform, toggle means pivotally supported on said base and having diverging portions movably connected to said bars, spaced rods rotatably carried by said bearing means and projecting through said openings for slidably guiding said bars lengthwise of said platform and each having oppositely threaded portions, spaced abutment means on each of said rods and having cooperative threaded means engaging said oppositely threaded portions, disengageable locking means to preclude displacement of said bars relative to said rods, helicoidal spring means interposed between said abutment means and bars for actuating the latter to shift said diverging portions towards each other to extend said toggle means to automatically elevate said platform pursuant to unlocking of said locking means, and key receiving means extending from said rods into said bearing means for rotating said rods for shifting said abutment means towards or away from each other to regulate the intensity of said springs.

7. In a posting stand, a base, a platform, bearing means on said platform, means carried by said base and platform for slidably guiding the latter towards or away from said base, shiftable bars arranged transversely of said platform and having guide openings, roller means carried by said bars and riding against said platform, toggle means movably interposed between said bars and base, spaced rods rotatably carried by said bearing means and projecting through said openings for slidably guiding said bars lengthwise of said platform and each having oppositely threaded portions, spaced abutment means on each of said rods and having cooperative threaded means engaging said oppositely threaded portions, disengageable locking means to preclude displacement of said bars relative to said rods, helicoidal spring means interposed between said abutment means and bars for actuating the latter to extend said toggle means to automatically elevate said platform pursuant to unlocking of said locking means, and key receiving means extending from said rods into said bearing means for rotating said rods for shifting said abutment means towards or away from each other to regulate the intensity of said springs, and indicating means to assist in controlling the intensity of said springs.

8. In a posting stand, a base, a platform, means carried by said base and platform for slidably guiding the latter towards or away from said base, shiftable bars arranged transversely of said platform and having guide openings, roller means carried by said bars and riding against said platform, toggle means having lower portions pivoted relative to said base and having upper diverging portions movably connected to said bars and actuated by the latter to extend said toggle means on elevating said platform relative to said base on movement of said bars towards each other and said upper portions being actuated away from each other to collapse said toggle on lowering of said platform for shifting said bars away from each other, spaced rods

carried by said platform and projecting through said openings for slidably guiding said bars lengthwise of said platform, abutment means on said rods, locking means to preclude displacement of said bars relative to said rods, and helicoidal spring means interposed between said abutment means and bars for actuating the latter to extend said toggle means to automatically elevate said platform pursuant to unlocking of said locking means.

9. In a posting stand, a base, a platform having slots, bearing means on said platform, means carried by said base and platform for slidably guiding the latter towards or away from said base, shiftable bars arranged transversely of said platform and having guide openings, roller means carried by said bars and riding against said platform, toggle means having lower portions pivoted relative to said base and having upper diverging portions movably connected to said bars and actuated by the latter to extend said toggle means on elevating said platform relative to said base on movement of said bars towards each other and said upper portions being actuated away from each other to collapse said toggle on lowering of said platform for shifting said bars away from each other, spaced rods rotatably carried by said bearing means and projecting through said openings for slidably guiding said bars lengthwise of said platform and each of said rods having oppositely threaded portions, spaced abutment means on each of said rods and having cooperative threaded means engaging said oppositely threaded portions, disengageable locking means to preclude displacement of said bars relative to said rods, helicoidal spring means interposed between said abutment means and bars for actuating the latter to extend said toggle means to automatically elevate said platform pursuant to unlocking of said locking means, key receiving means extending from said rods into said bearing means for rotating said rods for shifting said abutment means towards or away from each other to vary the intensity of said springs, posts extending from said abutment means and movably guided in said slots, and means to indicate the extent of displacement of said posts relative to said slots.

10. In a posting stand, a base, a platform, bearing means on said platform, means carried by said base and platform for slidably guiding the latter towards or away from said base, shiftable bars arranged transversely of said platform and having guide openings, roller means carried by said bars and riding against said platform, toggle means having lower portions pivoted relative to said base and having upper diverging por-
